UNITED STATES PATENT OFFICE.

ALBERT J. ELDON, OF MOUNT VERNON, NEW YORK, ASSIGNOR TO THE HODGMAN RUBBER COMPANY, OF TUCKAHOE, NEW YORK, A CORPORATION OF NEW YORK.

DESIGN FOR A RUBBER DOLL.

Application filed December 26, 1924. Serial No. 11,795. Term of patent 14 years.

To all whom it may concern:

Be it known that I, ALBERT J. ELDON, a citizen of the United States, residing at Mount Vernon, in the county of Westchester and State of New York, have invented a new, original, and ornamental Design for a Rubber Doll, of which the following is a specification, reference being had to the accompanying drawings, forming a part thereof.

In the drawings Fig. 1 is a front view of the doll; Fig. 2 is a side view thereof, and Fig. 3 is a rear view.

I claim:

The ornamental design for a rubber doll substantially as shown.

ALBERT J. ELDON.
